DESIGN FOR A PLAQUE OR SIMILAR ARTICLE

Bradford B. Flint, Lake George, N. Y.

Application April 21, 1942, Serial No. 106,642

Term of patent 3½ years

To all whom it may concern:

Be it known that I, Bradford B. Flint, a citizen of the United States, residing at Lake George, in the county of Warren and State of New York, have invented a new, original, and ornamental Design for a Plaque or Similar Article, of which the following is a specification, reference being had to the accompanying drawing, forming a part thereof.

The drawing herewith represents a plan view of a plaque or similar article, illustrating my design.

The plaque or similar article is of no appreciable or substantial thickness.

I claim:

The ornamental design for a plaque or similar article, as shown and described.

BRADFORD B. FLINT.
